poration, New York, N. Y., a corporation of New
York

Application August 8, 1940, Serial No. 351,871

11. Claims. (CL 178—44)

The present invention relates to electric wave translation systems and methods of operating same, more particularly to a wave filter for translating modulated carrier signal energy.

There frequently arises the problem in practice in electric wave translation systems or filters for transmitting modulated signal energy to amplify a discrete band of frequencies and to eliminate all other frequencies. Specifically, in radio or similar receivers for modulated signal energy it is desirable to amplify a band of frequencies including the carrier and the side band frequencies characteristic of the signal or message being transmitted and to completely eliminate all frequencies outside the highest side band frequency desired to be received in order to minimize or suppress the reception of interfering signals.

The above object is usually accomplished by a system of cascaded resonant circuits designed to offer high impedance to the desired frequency band and to offer a substantially lower impedance to frequencies outside the desired frequency band.

The known systems used at the present have the disadvantage of requiring a large number of cascaded amplifier stages to yield anything like sharp attenuation of the undesired frequencies. A further disadvantage of the known systems is the fact that they employ band-pass filters with greater than optimum coupling and, accordingly, the tuning of one of the elements of the filter reacts upon the other elements in such a manner as to make proper alignment and tuning extremely difficult.

There is also the problem of obtaining extreme selectivity in a communication type receiver. Heretofore, this has required the employment of a great number of cascaded amplifying stages. On the other hand, the number of cascaded stages that may be used is limited in practical design due to inherent tube noise, self-oscillation, physical space considerations and various other requirements. Moreover, the use of a number of sharply tuned cascaded stages tends to sharpen the entire resonance curve rather than to eliminate the outer portions or skirts without cutting the peak. In other words, these methods are not adapted to approach the ideal of a flat top curve with sharp cut-offs desirable in practice. As a result of this drawback the desired side bands are reduced or suppressed when extreme selectivity is desired resulting in signal distortion and other defects.

A further problem met with in practice, es-

pecially in the design of superheterodyne receivers is to substantially eliminate the second channel or image frequency interference from the first detector or converter stage without the use of an undue number of radio frequency pre-selector stages or without the use of complicated band-pass circuits preceding the converter stage.

Accordingly, it is an object of the present invention to provide new and novel means for accomplishing the above results in a simple manner, thereby removing the need for an increased number of cascaded amplifier stages with their attendant difficulties and providing an electric wave translation system or filter having a frequency response characteristic which may be adjusted easily to have any desired shape to suit existing design requirements.

Another object is to provide a wave filter having a minimum of inter-action between the tuned circuits forming the elements of the filter.

A further object is to provide means for obtaining extreme selectivity in a radio or equivalent receiver by utilizing a minimum of tubes and parts and for providing a high degree of stability compared with arrangements heretofore employed in the art for accomplishing the same purpose.

Still another object is to provide a multiplex communication system using a minimum of tubes and associate apparatus for allowing a maximum of messages to be transmitted through a single channel of given frequency band width.

Still a further object is to provide a wave analyzer adapted to allow the determination and accurate measurement of the fundamental frequency and the various harmonic components of a complex electric wave.

Another object is to provide a simple and effective means for rejecting the image frequency in a superheterodyne receiver.

These and further objects and aspects of the invention will become more apparent as the following detailed description proceeds taken with reference to the accompanying drawings forming part of this specification and wherein:

Figure 1 is a basic circuit diagram of a selective filter or translation system embodying the principles of the invention.

Figure 2 is a diagram of a radio frequency amplifier and detector embodying a selective filter for varying the frequency response characteristic of the detected signal in accordance with the invention.

Figure 3 is a modified diagram of a radio frequency amplifier and detector for receiving am-

plitude modulated carrier signals and embodying a selective filter according to the invention for varying the frequency response characteristic,

Figures 4A to 4E are explanatory graphs illustrating the variation of the frequency response curves of an amplifier shown in Figures 2 and 3,

Figure 5 shows the variation of the detected audio frequency wave obtained from Figure 2,

Figures 6A to 6E show the variation of the wave shape of the audio frequency output current or voltage of Figure 2 when using a high-Q resonant impedance in the filter circuit according to the invention such as a piezo-electric crystal as shown in Figure 9,

Figures 7 to 10 illustrate further modifications of basic circuits embodying the principle of the invention,

Figures 11A to 11F show further resonance or frequency response curves which may be obtained from systems constructed in accordance with the invention,

Figure 12 is a vector diagram explanatory of the function of the invention.

Figures 13 to 17 show still further modifications of basic circuits embodying the principle of the invention,

Figure 18 is a diagram showing the radio frequency spectrum of a modulated wave including distortion components,

Figure 19 shows a practical embodiment of the invention for analyzing the distortion components contained in an electrical wave,

Figure 20 shows the variation in plate current in the circuit of Figure 19 as a function of frequency,

Figure 21 shows a complete radio receiver embodying a band-pass system of the type according to the invention,

Figure 22 illustrates schematically a further embodiment of the invention for multiplex communication through a single signalling channel, and

Figure 23 illustrates the employment of the invention in a superheterodyne receiver to effect rejection of the image frequency signal.

Like reference characters identify like parts throughout the different views of the drawings.

Referring more particularly to Figure 1, there is shown a simple circuit constructed in accordance with the principle of the invention. Item 10 is an electron discharge tube in the example shown a tube of the hexode type comprising a cathode 11, a first input or signal control grid 12, a further control grid 13, a screen grid 14 located between the control grids 12 and 13 and an anode or plate 16. If in a tube of this type the control grids 12 and 13 are suitably negatively biased with respect to the cathode 11, such as by the provision of a biasing network 17, comprising a resistance and a shunt and by-pass condenser placed in the cathode-to-ground lead or by any other suitable biasing arrangement, and if suitable positive potentials are applied to the screen grid 14 and to the plate 16 with respect to the cathode, electrons emitted from the cathode 11 will be accelerated through the meshes of the first control grid 12 towards the positive or screen grid 14. Most of the electrons will flow through the relatively wide meshes of the screen grid and form a concentrated space charge or virtual cathode in the region between the screen grid 14 and the second control grid 13. The magnitude of this space charge or virtual cathode and its distance from the control grid 13 is a function of the magnitude of the positive potential on the

grid 14, the negative potentials on the control grids 12 and 13, and of the intensity of the electron space current emitted from the cathode 11.

If a radio frequency signal is impressed between the input grid 12 and the cathode 11 which signal may be supplied from any suitable source preceding the input terminals *a*—*b*, a voltage will be set up on grid 12 causing the electron stream flowing from the cathode 11 to the virtual cathode to be varied or modulated, that is, the charge density of the virtual cathode adjacent to the control grid 13 will fluctuate at the frequency of the input signal. Item 20 is an impedance element having a value Z_t connected between the grid 13 and ground. If this impedance Z_t is of purely resistive character, it will be found that a displacement current will be induced in the circuit of grid 13 flowing from this grid through the resistance to the cathode. This current is of the same frequency as the input signal but phase shifted by 90° with regard to the input potential on the grid 12. In other words, the current from the grid 13 through the resistive impedance Z_t to ground will be phase shifted by 90° with respect to the signal voltage between the grid 12 and cathode 11. If the impedance element 20 between the grid 13 and ground or cathode has the form of a parallel resonant circuit and the resonant frequency of this parallel resonant circuit is varied about the frequency of the incoming signal the following phenomena will be observed.

Whenever the resonant frequency of impedance 20 is equal to the frequency of the incoming signal impressed by way of terminals *a*—*b*, Z_t will offer pure ohmic resistance to the quadrature potential induced on the grid 13 and accordingly the voltage across grid 13 and ground or cathode will be in phase with the current through this circuit and the potential established on the grid 13 will therefore be phase shifted by 90° with respect to the potential on the input grid 12. If the impedance element 20 is tuned to a frequency slightly higher or slightly lower than the frequency of the incoming signal, Z_t will offer capacitive or inductive reactance to the displacement current depending on the sense of departure of the resonant frequency of impedance 20 from the frequency of the incoming signal. Accordingly, therefore, the voltage developed between the grid 13 and cathode or ground will either lag the current through the circuit by 90° or lead the current by 90° depending upon the sense and magnitude of the relative frequency departure between the resonant frequency of 20 and the impressed signal frequency. Consequently the resultant voltage developed on the grid 13 will be either in phase with the voltage on the grid 12 or 180° out of phase with the latter. By suitably tuning impedance 20 to either the signal frequency or a frequency above or below the frequency of the input signal any intermediate degree of phase shift between the values 0° and 180° may be obtained for the potential established on grid 13 with respect to the potential on grid 12.

An analysis of the grid current in a vacuum tube of the type shown comprising a pair of control grids placed in the path of the electron space current and having potentials of the same frequency but varying relative phase angle impressed upon said grids shows that the plate output current may be represented substantially by the following formula:

$$i = a_1 e_1 k_1 E'' + a_2 e_2 E' + a_1 a_2 e_1 e_2$$

provided higher order terms may be neglected

and with k_1, k_2, a_1, a_2 representing constants depending on the tube characteristics, and with E' and E'' representing the steady grid bias voltages and e_1 and e_2 representing the alternating voltages impressed upon or established on the control grids. The first two terms of the above formula will cause a vectorial resultant current in the output circuit which will develop a potential varying in dependence upon the resultant phase angle between the grid voltages e_1 and e_2 . From this it will be seen that by suitably tuning the resonant impedance means 20, any desired frequency or band of frequencies may be substantially rejected or accentuated in the output circuit to obtain a desired response characteristic as will be further explained with reference to the vector diagram shown in Figure 18.

Item 18 in Figure 1 is a by-pass condenser connected between the screen grid 14 and ground in a manner well known. The output circuit of the tube may contain any suitable coupling impedance Z_0 designated by numeral 21 to develop output voltage between terminals $c-d$. Item 22 is a by-pass or smoothing condenser to eliminate fluctuations of the plate voltage in manner well understood. Impedance 24 may be designed to respond to either audio or radio frequency variations of the plate current. For example it may be comprised of an ohmic resistance shunted by a radio frequency by-pass condenser as shown in Figures 2, 7 to 9, 13, 16 and 17, said by-pass condenser offering little or no impedance to the radio frequency components and offering high impedance to the modulating signal such as audio frequency signal components of the plate current. Alternatively, the impedance 24 may be a low-pass filter as shown in Figure 19 or a radio frequency impedance as shown in Figures 3, 10, 14, 15, 21 and 23 as will be further described hereafter.

The system as described is especially suited for modifying the response characteristic of a translation circuit for an amplitude modulated carrier signal e comprising a carrier component and upper and lower side bands as represented by the following general formula well known to those skilled in the art:

$$e = E_0 \sin 2\pi f t + \frac{ME_0}{2} \cos 2\pi(f - f_s)t - \frac{ME_0}{2} \cos 2\pi(f + f_s)t$$

wherein f_s represents the modulating frequency such as a sound wave, f represents the carrier frequency and M the modulation index. This input voltage is applied to the control grid 12 in such a manner that the potentials at the grids 12 and 13 will vary in phase and amplitude depending on the tuning adjustment of the resonant impedance means 20 connected between the control grid 13 and cathode or ground. Accordingly, in the output circuit either one of the side bands

$$\frac{ME_0}{2} \cos 2\pi(f - f_s)t$$

or

$$\frac{ME_0}{2} \cos 2\pi(f + f_s)t$$

or one side band and the carrier $E_0 \sin 2\pi f t$, or both side bands may be accentuated or attenuated depending on the tuning adjustment of the resonant impedance 20. This applies to a single side band frequency considered in the above

formula or to an extended band of side frequencies if a complex modulating wave such as music or speech is employed in a manner well known.

Accordingly, therefore, the output frequency developed across the impedance 21 will either attenuate or accentuate within limited frequency ranges the component audio or other modulating signal wave and the response curve of the system will be of the type as shown in Figures 4A to 4E to be explained hereafter.

If impedance 20 is a radio frequency impedance such as a parallel resonant circuit tuned to the frequency of the input signal, there will be developed a radio frequency potential across the output terminals $c-d$ comprising a band of radio frequencies (side bands) corresponding to the modulating frequency wave and the carrier and the side bands of the input signal will be amplified differentially in dependence upon the tuning adjustment for the resonant impedance 20, in a manner as is readily understood from the above. Thus, one side band and the carrier may be attenuated or accentuated, or the carrier alone may be accentuated or attenuated or finally, a single side band may be modified in a similar manner depending on the relative detuning of the resonant impedance 20 with respect to the input signal frequency.

Referring to Figure 2, there is shown a two-stage radio frequency amplifier feeding a selective detector stage constructed in accordance with the invention to modify the frequency response characteristic of the system. The radio frequency amplifier stages are of standard design comprising a pair of pentode vacuum tubes 24 and 25, a tuned inter-stage coupling transformer 26 and a tuned output transformer 27. The secondary voltage supplied by the latter is impressed between the grid 12 and cathode 11 of a detector tube 10 of substantially the same type as shown in Figure 1, embodying a parallel tuned circuit comprised of a variable condenser 30 and an inductance 31 forming a resonant impedance means connected between the control grid 13 and ground or cathode. The circuit 30-31 is suitably isolated or magnetically shielded from the remaining parts of the system such as by the aid of a grounded metallic screen indicated at 32. The tube is biased to operate as a plate detector and includes a low-pass coupling network in the plate circuit comprising a series resistance 34 and a pair of by-pass condensers adapted to develop an audio frequency potential impressed by way of coupling condenser 33 upon the vertical deflecting plates 36 and 37 of a cathode ray oscilloscope connected between the output terminals $c-d$, said oscilloscope having a pair of horizontal deflecting plates 40 and 41. The positive potential applied to the screen grid 14 of the detector 10 is regulated to a substantially constant value by the aid of a gas discharge tube 28 placed between the screen grid and ground in a manner well understood. The screen grid is by-passed for radio frequencies by a condenser 18 and a suitable operating point on the tube characteristic is obtained by the aid of a biasing resistor and condenser combination 17 in the cathode-to-ground lead in substantially the same manner as described with reference to Figure 1. The tuned circuit 30-31 comprising an inductance and a condenser in parallel and offering an impedance Z_0 , Figure 1, is resonant to a frequency close to the frequency of the incoming signal impressed by way of terminals $a-b$ and accordingly a phase shifted potential of the same frequency as the incoming signal

will be developed upon the grid 13, the magnitude and sense of the phase shift being proportional to the departure of the resonant frequency of the circuit 30-31 from the incoming signal frequency. Accordingly, therefore, in the output circuit of tube 10 there will be a variation in the voltage developed across the resistor 34. The shunt condensers for the latter will by-pass all radio frequencies from the plate circuit and thus only audio frequency variations will be developed across the resistor 34. The overall resonance curve of the amplifier may be substantially controlled by suitably adjusting the circuit 30-31 to a resonant frequency at or near the frequency of the incoming signal and the output current or potential may be visibly observed on the screen of the cathode ray oscilloscope 35 as a function of the setting of the variable condenser 30 of the resonant impedance in a manner to be further described hereafter.

If an unmodulated radio frequency input signal is varied about its normal frequency, resonance or frequency response curves as shown in Figures 4A to 4E may be obtained, the different response curves corresponding to different settings of the condenser 30. For example, if the input frequency is varied very rapidly such as by electronically controlled reactance means there will be visibly traced on the screen of the oscilloscope resonance curves of the type shown on Figures 4A to 4E provided a sweep voltage equal to said frequency variation is impressed upon the horizontal plates 40, 41 of the oscilloscope.

Figure 5 shows the variation of the output voltage v as a function of the setting m, n, o, p and q of the tuning condenser 30 obtained on the screen of the oscilloscope from a system of Figure 2 or Figure 3 when an amplitude modulated input signal is held at a constant frequency and a suitable time base voltage is applied to the horizontal deflecting plates of the oscilloscope.

Figure 2 shows a circuit embodying the principle of the invention in the form of a detector for modulated radio waves to effect a variable frequency response in the detected output current. Figure 3 shows a radio frequency amplifier and detector of the same type as shown in Figure 2 with the exception that the frequency response control tube 10 is used as a radio frequency amplifier rather than as a detector and the radio frequency output signal is detected separately in a known manner by a diode detector 45. The frequency response is controlled in the same manner as in Figure 2 by adjusting the tuning frequency of the resonant impedance means, in the example shown the parallel tuned circuit 30-31 connected between the virtual cathode-excited control grid 13 and cathode or ground in the manner proposed by the invention. Items 42 and 43 represent the pre-amplifying stages shown schematically. Item 44 is the resonant output transformer for the tube 10 energizing the rectifying circuit comprising diode 45 and a load resistance 46 shunted by a condenser 47. The rectified potential developed by the resistance 46 is impressed between the vertical deflecting plates 36 and 37 of the oscilloscope 35 in a manner similar to that shown in Figure 2.

Referring again to Figure 2, if the tuned resonant circuit 30-31 is replaced by a resonant impedance having a substantially higher Q such as a quartz crystal shunted by a high ohmic impedance to provide a direct current return path for the control grid 13 such as shown in detail in Figure 9, it is found that the selectivity curve of the system will be greatly sharpened. If a

radio frequency carrier f modulated according to a frequency f_s in the manner described before is impressed between the input terminals $a-b$ of such a system, there will be present at the input the carrier frequency f and a number of side frequencies as shown in Figure 18. Actually, if the modulation is accomplished without distortion and if the modulating frequency contains no harmonics there will be present only the first positive and negative side band frequencies as shown in Figure 18 which side bands are removed from the carrier frequency f by values $\pm f_s$, respectively. However, in case of second and higher harmonic distortion in f_s , or due to the modulation process, there will be other side bands or frequencies generated by these harmonics, said side bands having frequencies $f-2f_s, f+2f_s, f-3f_s, f+3f_s$, etc., as shown in Figure 18.

It has been found that the aforescribed circuit of Figure 2 embodying a sharply tuned impedance such as a quartz crystal shunted by a high ohmic resistance (see Figure 9) is sufficiently selective to accentuate anyone of the side bands and at the same time substantially attenuate all the other side bands in such a manner as to afford a visual observation and study of either the first side band or the higher order side bands obtained in the demodulated signal as will become further apparent from Figure 6.

In the latter there are shown traces (voltage v as a function of time) produced on the screen of the oscilloscope representing various wave forms of the detected or output signal if an input carrier signal having a frequency f modulated in amplitude by an audio frequency f_s is impressed upon the input circuit and if the carrier frequency f is varied slightly so that the various side bands will assume a definite relation to the resonant frequency of the crystal or other high-Q impedance means, so as to accentuate any desired frequency, this being the equivalent of keeping the carrier frequency fixed and varying the tuning of the resonant impedance connected to grid 13.

Figure 6A shows the normal curve obtained from the detector by demodulating a carrier f modulated in accordance with an audio frequency f_s , the latter being represented by the curve in Figure 6A.

Figure 6B shows the demodulation of the second order side band obtained by adjusting the carrier frequency to another value thus indicating a harmonic content of the wave due to distortion of the modulating wave or distortion introduced during the modulation process.

Figure 6C shows the demodulation of the third order side band obtained by adjusting the carrier frequency to still another value, indicating that a third harmonic component is present in the modulating frequency f_s or has been introduced during the modulation process.

Figure 6D shows another shape of the fundamental frequency comprising the first side band with a fairly high order of third harmonic content.

Figure 6E shows the relative shape in output amplitude as a function of change of the resonating frequency of the circuit 30-31 using a high-Q tuned circuit or a piezo electric crystal provided with either a variable condenser shunted across the crystal or means to vary the pressure applied to the crystal or the spacing between the crystal holder plates. In this case the input signal, Figure 2, is amplitude modulated and held at a constant frequency and a suitable time

base voltage is applied to the horizontal deflecting plate.

Referring to Figures 7 to 10, there are shown modifications of circuits embodying the basic principle of the invention. In Figure 7 a series tuned path comprising an inductance 50 and a condenser 52, the latter being shunted by a high ohmic resistance 53 to provide a direct current grid return path for the control grid 13, is provided in place of the parallel tuned circuit 30-31 shown in the preceding illustrations. By suitably varying the resonant frequency of this series tuned circuit the phase of the potential established on the grid 13 may be varied from 0 to 180° with respect to the phase of the input potential upon the grid 12 and accordingly in the plate circuit of the tube a variable frequency response will be obtained in substantially the same manner as described hereinbefore. The tube may again serve either as a detector or high frequency amplifier as is understood from the above. In the example illustrated, the tube serves as a detector and for this purpose has a low frequency or audio network inserted in its plate circuit comprised of a series resistance 55, a by-pass condenser 54 and a blocking condenser 57 to produce a low frequency or audio signal voltage between the output terminals c—d.

Referring to Figure 8, the same is similar to the preceding figure with the exception that a band-pass filter is provided connected to the control grid 13 as a phase shifting impedance means. This band-pass filter in the example illustrated comprises a pair of parallel resonant circuits 60-62 and 61-63 having their low potential sides directly connected and having their high potential sides connected through a coupling condenser 64. By varying the central resonant frequency of this band-pass filter the phase shift of the potential established on grid 13 may be varied with respect to the phase of the input potential impressed upon the grid 12. At or about the central resonant frequency of the band-pass filter the phase shift will be substantially constant, and at frequencies slightly remote from the center frequency of the filter the phase shift will vary very rapidly. Accordingly, therefore, there will be nearly a constant phase shift of 90° of the potential upon the grid 13 with respect to the potential upon grid 12 at one discrete band of frequencies, and at frequencies even slightly remote from this band the phase angle between the potentials on the grids 12 and 13 will vary rapidly and consequently a variation of the output response of the circuit will be obtained substantially as shown in Figures 4D and 4E. As will be understood, any other filter or time delay circuit connected to the grid 13 may be employed for the purpose of the invention to modify the frequency response characteristic in the manner described.

Referring to Figure 9, there is shown a system similar to the preceding diagrams embodying a quartz crystal 65 or an equivalent electro-mechanical resonating element connected between the control grid 13 and ground or cathode. The quartz crystal is shunted by a high ohmic impedance 66 to provide a direct current return path from the control grid 13 to the cathode of the tube. This resistance 66 may be varied to vary the Q of the crystal in order to obtain a broader response curve if desired. The operation of this system is similar to systems embodying a resonant circuit described hereinabove.

Figure 10 shows a circuit similar to Figure 9

wherein the single crystal 65 has been replaced by a band-pass filter comprising three crystals by shunting a pair of further crystals 67 and 68 connected in series across the crystal 65 in the manner shown in the drawing. By using three crystals of slightly different frequency, the phase shift of the potential on grid 13 may be controlled in such a manner as to obtain a flat top resonance curve with extremely steep sides.

10 In this figure, the tube 10 is assumed to act as a radio frequency amplifier by the provision of a radio frequency transformer 70 in the output circuit.

Figures 11A and 11F show response curves obtained with a resonant impedance means connected to the control grid 13 having an extremely high Q value to enable rejection or accentuation of a single or limited number of frequencies compared with the curves of Figure 4A to Figure 4E based on substantially lower Q values of the resonant impedance means and resulting in a substantial number of component frequencies being affected by the selective control action of the grid 13.

25 Figure 11A shows a normal response curve of an amplifier (output voltage v as a function of the frequency f) with the resonant impedance means according to the invention disconnected from the grid 13. This represents the well known resonance characteristic of a tuned circuit or system for a carrier frequency f_0 .

30 Figure 11B shows the effect of providing a single high-Q resonant circuit tuned so as to accentuate the carrier frequency and the frequencies on one side of the carrier and to attenuate the frequencies on the other side of the carrier.

35 Figure 11C is a similar resonant curve for a two-stage selective amplifier wherein one resonant impedance provided in one stage according to the invention is tuned to a frequency below the carrier frequency and another resonant impedance associated with the other stage is tuned to a frequency above the carrier frequency, resulting in a symmetrical or flat top characteristic of desired band width.

40 Figures 11D, 11E, and 11F correspond, respectively, to Figures 11A, 11B, and 11C showing a further increase of the sharpness or cut-off of the resonance curves by further increasing the Q of the resonant impedance such as by using a quartz crystal or a tuned circuit with an associate damping reduction system as shown in Figure 16 to be describe hereafter.

45 Figure 12 is a vector diagram being further explanatory of the principle and function of the invention. Vectors e_1 and e_2 represent the potentials on the grids 12 and 13, respectively, for a particular frequency which potentials are at a 90° phase as shown if the resonant impedance connected to grid 13 is in exact tune with the respective input frequency. If the resonant impedance is detuned relative to the input frequency, the phase angle of the potential e_2 relative to e_1 will become smaller or greater than 90° depending on the sense of detuning as shown at e_2' and e_2'' , respectively. The output potential being proportional to the vectorial sum of the potentials e_1 and e_2 will vary accordingly as shown by the vectors E , E' and E'' , respectively, resulting in an attenuation or accentuation of the respective frequency which may be a component of a modulation frequency band. Depending on the Q-value of the resonant imped-

ance controlling the phase on grid 13, a lesser or greater number of component frequencies will be affected resulting in a corresponding modification of the resultant frequency response characteristic of the system. In addition to the sum terms in the equation of plate current as a function of the vector potentials on the control grids, the product term will likewise yield a variation in plate current due to the phase shift of the potential on the second grid with respect to the potential impressed upon the first grid.

From the foregoing it will be apparent that it is not necessary for the resonant impedance to be connected between the grid 13 and cathode, but rather that it is only necessary that this impedance be arranged in a manner so as to change the phase of the potential established on the control grid 13 with respect to the input potential impressed upon the grid 12. Accordingly, therefore, Fig. 13 shows a resonant impedance means, in the example shown in the form of a quartz crystal, connected between the two control grids 12 and 13. In an arrangement of this type the potential on grid 13 will be in phase with the current through the crystal if the input frequency equals the resonant frequency of the crystal. Above and below the resonant frequency of the crystal the potential developed on grid 13 will be phase shifted with respect to the input potential on grid 12 as is understood from the above.

If the crystal in Figure 13 is replaced by a resonant circuit, the operation will be in a similar manner. For example, on resonance the phase shift caused by the virtual cathode, ordinarily 90°, will be neutralized since the condenser formed by the virtual cathode and the grid 13 plus the tuning condenser of the parallel resonant circuit connected between the grids 12 and 13 will resonate with the inductance to the desired frequency and accordingly the phase angle between the grid potential will be zero and the grids will be effectively coupled by a pure ohmic resistance. Above and below the resonant frequency there will be a varying phase shift between the potential on grid 13 with respect to the input potential on grid 12 in substantially the same manner as described hereinabove.

According to another modification, the functions of the grids 12 and 13 may be interchanged, that is, the input signal may be impressed upon the grid 13 while the resonant impedance means is connected to the grid 12 and cathode as shown in Figure 14 (parallel tuned circuit 30-31). The operation of this arrangement is substantially the same as has been previously described.

Figure 15 shows a further variation of the invention wherein the vacuum tube 10 is provided with three control grids viz. the input grid 12, a first control grid 13 and an additional control grid 13', all the three control grids being effectively shielded by a common screen grid 14 connected and biased in the same manner as described above. A first resonant impedance such as parallel tuned circuit 30-31 is connected between the grid 13 and cathode as in the previous circuits and an additional resonant circuit 30'-31' is connected between the grid 13' and cathode. By suitably detuning the circuits 30-31, 30'-31' above and below, respectively, the frequency of the input signal, a band-pass type filter will be obtained as is understood from the above. The characteristic of such a filter will be as shown in Figures 4D and 4E.

Referring to Figure 16 there is shown a means for increasing the Q-value of the parallel tuned circuit 30-31 serving as a resonant impedance connected to the control grid 13. For this purpose, there is shown a de-damping circuit or "negative" resistance in the form of a two-stage resistance coupled amplifier comprising a pair of screen grid amplifier tubes 75 and 78 connected in cascade through a resistance coupling network 77 of known design. The tube 75 has its grid cathode path shunted across the circuit 30-31. Item 76 is a degenerative resistance in the cathode lead of this tube and 80 is a biasing network in the cathode-to-ground lead for the tube 78. The output of tube 75 is connected to the input of tube 78 through a pair of feedback paths one being of regenerative and the other being of degenerative character and containing adjustable resistors 81 and 82, respectively, to provide by differential feedback a "negative" resistance shunted across the circuit 30-31 to decrease its damping or increase its Q-value. In this manner by controlling the damping reduction of the circuit 30-31 in addition to the control of the tuning adjustment it is possible to greatly increase the flexibility of the system to suit any practical requirements.

Referring to Figure 17, there is shown another modification of an inventive circuit comprising a pair of electron tubes in place of the single composite tube 10 provided in the preceding diagrams to obtain the results according to the invention. The input signal voltage is impressed upon the grid 85 of an ordinary screen grid tube 84 including a screen 86 and a plate 87. The resonant impedance such as a parallel tuned circuit 30-31 is connected between the plate 87 and cathode, that is the plate is operated at substantially cathode potential or at a negative potential with respect to the cathode. Due to the virtual cathode formed adjacent to the plate 87 in a manner understood from the foregoing, the circuit 30-31 will develop a phase shifted potential on the plate 87 relative to the input potential on grid 85. In order to produce a combined effect of the potentials on the grid 85 and plate 87 a further tube 88 having a pair of control grids 90, 91 which may be separated by a screen grid 92, and having a plate 93 is provided in the embodiment shown. Control grid 90 is excited by the potential developed at the plate 87 and control grid 91 is excited by the input potential wherein a radio frequency or audio frequency voltage will be developed in the output circuit of tube 88 of modified frequency characteristic in substantially the same manner as described hereinbefore.

Figure 19 illustrates a further application of the invention in the form of a wave analyzer of the harmonic type for determining and studying the harmonic content of electric waves. As has been shown above, if a radio frequency carrier having a frequency f is modulated in accordance with an audio frequency f_a there will be present in the modulation product the carrier frequency and a plurality of upper and lower side band frequencies as shown in Figure 18. If f_a contains distortion components, that is if it is not free from harmonics it may be thought of as containing the following frequencies: $f_{a1} + 2f_{a1} + 3f_{a1} \dots nf_{a1}$. In other words, f_a will be a composite periodic wave containing a fundamental frequency f_{a1} plus harmonics of both odd and even order. In Figure 19, item 95 is a variable oscillator producing a stable oscillation and being

accurately calibrated; 96 is a buffer amplifier of the band-pass type having a flat frequency response throughout the band over which the oscillating frequency is to be varied; 97 is a modulating amplifier also having a flat frequency response over the frequency variation range of the oscillator 95. There is further provided an audio frequency amplifier 99 whose gain may be varied and which is flat over the entire audible and supersonic range. 98 represents the input circuit for impressing an unknown audio or supersonic wave whose fundamental frequency and harmonic content it is desired to measure. The output of the modulating amplifier 97 is fed through a suitable attenuator 100 and hence to the first control grid 12 of valve 10 having a quartz crystal 65 connected to the second control grid 13 in a manner described hereinabove. 101 is an audio-frequency filter in the output circuit of tube 10 to develop a voltage impressed upon the vertical deflecting plates 104-104' of a cathode ray oscilloscope 102 on the one hand and upon a vacuum tube voltmeter 105 on the other hand. Horizontal deflecting plates 103-103' of the oscilloscope are excited by a suitable linear time base.

The operation of the system of Figure 19 is as follows: The amplifier 97 is modulated to a certain percentage by the unknown frequency applied by way of input 98 by suitably varying the gain of the amplifier 99. The oscillator 95 is then set to the frequency of the crystal 65 by observing the vacuum tube voltmeter 105. The plate current i of the latter as a function of frequency varies as shown in Figure 20 when the frequency of the oscillator 95 passes through the frequency of the quartz crystal. The oscillator is set to the central operating point P and the attenuator 100 adjusted so that practically no indication appears on the screen of the oscilloscope as marked in Figure 20. Then the oscillator 95 is increased or decreased slowly in frequency to a first point until an audio frequency wave is impressed upon the oscilloscope 102. The vacuum tube voltmeter 105 shows that an audio frequency voltage is impressed at the output of the wave filter. The difference in frequency of the oscillator 95 from its setting at the operating point P to this first point is then the fundamental frequency f_0 of the wave being analyzed. Its amplitude may then be set to a predetermined value of say 100% on the vacuum voltmeter by varying the gain of the amplifier 99. The oscillator is then varied further in frequency until a second point is found and an audio signal is present on the screen of the oscilloscope. This curve may approximate that shown by Figure 6B and will include the second harmonic $2f_0$. The relative amplitude of the second harmonic may be noted on the vacuum tube voltmeter. In a like manner the third harmonic may be visually observed and its amplitude determined. Accordingly, therefore, a complete analysis of an unknown audio frequency wave may be readily obtained with this system utilizing the principle of the invention. In an alternative arrangement the oscillator 95 may be fixedly tuned and the crystal 65 may be varied with respect to the oscillating frequency or an extremely high-Q resonant impedance of variable resonant frequency may be employed in place of the crystal. Similar results are obtained by holding the oscillator at a fixed frequency and by varying this resonant impedance. For example, in actual practice a tuned circuit followed by an amplifier comprising both degener-

ative and regenerative feedback to control the effective Q of the resonant impedance as shown in Figure 16 may be advantageously employed in an analyzing system of this nature.

Referring to Figure 21 there is shown a complete radio receiver embodying the principle of the invention. The incoming signals received by an antenna 110 are impressed by way of a tuned coupling transformer 111 upon the input of a frequency converter or first detector stage 112 wherein the radio frequency signals are combined with signals of a local oscillator 113 to produce signals of intermediate frequency impressed upon an intermediate frequency amplifier by way of a transformer 114 fixedly tuned to the intermediate frequency. The intermediate frequency amplifier in the example shown comprises two amplifier stages constructed in a manner proposed by the invention; each comprising a phase shifting resonant circuit 116 and 120, respectively, connected to the second control grid of the amplifier tubes 115 and 118 and being suitably tuned below and above, respectively, the intermediate frequency to obtain a resultant frequency response characteristic of any desired shape. The output of stage 115 is coupled to the input of stage 118 through a tuned intermediate frequency transformer 117. The amplified intermediate frequency signals are impressed upon the second detector including a diode 122 followed by an audio frequency amplifier and a translating device such as a loud speaker in accordance with standard practice. Automatic volume control voltage may be obtained from the diode detector and employed to control the direct current bias on the control grids of the intermediate frequency amplifier. By replacing the tuned circuits 116 and 120 by quartz crystals, it is possible to obtain a resonance curve with extremely sharp cut-offs for the receiver. This is particularly useful in communication type receivers where it is desirable to receive a signal in the presence of an interfering signal only a few cycles away. It has also been found advantageous to make the resonant frequency of one of the crystals variable over a few kc. and to have it controlled from the front panel of the receiver to allow efficient "single signal reception."

It has been found that by varying the Q of Z_1 in Figure 1, the sharpness of the response variation may be varied over wide limits. In practical design of high fidelity superheterodyne receivers it is usually desirable to connect a variable resistor across Z_1 to vary its Q value in such a manner as to obtain a flat top response curve over the desired frequency range say about 20 kc. Once this has been determined the Q of the tuned circuit with the resistor shunted across it is measured and the tuned circuit is replaced by a circuit having a desired Q value.

Figure 22 illustrates a further application of the invention embodied in a multiplex telegraph system. A carrier frequency f generated in the transmitter 126 is modulated by a number of modulating frequencies f_1, f_2, f_3 produced by generators 126, 127, 128, etc. At the receiving end a number of receivers 130, 132, 133, etc. each including a circuit of the type proposed by the invention are provided, each including a quartz crystal 65 to serve as selective means for segregating the several modulating frequencies f_1, f_2, f_3 and f_4 and applying them to the respective receivers operating suitable translating devices such as earphones 131 or the like.

By utilizing a system according to the invention

in the preselector stage of a superheterodyne receiver and suitably tuning the resonant impedance Z_r to the image frequency of the receiver, the latter may be greatly minimized or suppressed while at the same time augmenting the amplitude of the desired signal frequency. An arrangement of this type is shown in Figure 23 wherein tube 10 constitutes a radio frequency amplifying stage connected between the antenna 110 and the frequency converter or mixer 135 of the superheterodyne receiver. By suitably tuning the resonant circuit 30-31 connected to the second control grid of the tube in the manner described and by properly tracking and ganging the tuning condenser 31 with the local oscillator and the remaining radio frequency tuning elements, the image frequency may be rejected substantially within a desired operating range.

It will be evident from the foregoing that the invention is not limited to the specific circuits and arrangements shown and disclosed herein for illustration but that the principle and underlying inventive idea are susceptible of numerous variations and modifications coming within the broader scope and spirit of the invention as defined in the appended claims. The specification and drawings are accordingly to be regarded in an illustrative rather than a limiting sense.

I claim:

1. In a system for translating a modulated signal wave comprising a carrier and a predetermined band of side frequencies, an input circuit, an electron discharge device comprising a cathode and an anode for producing an electron space current, control means including circuit connections from said input circuit to said electron device for varying said space current in accordance with said signal wave, an electrostatic control electrode in said device, means for producing a concentrated variable electron space charge adjacent to said control electrode, an output circuit for said device, the input-output frequency characteristic of said system having a band width sufficient to pass said carrier and side frequency band, resonant impedance means connected to said control electrode and cathode, said impedance means having a frequency response characteristic of substantially reduced band width compared with said input-output frequency characteristic and having its center frequency detuned relative to said carrier frequency to establish a potential upon said control electrode for discrete components of said signal wave of such phase as to modify said input-output frequency response characteristic.

2. In a system for translating a modulated carrier signal wave comprising a carrier and a predetermined band of side frequencies, an input circuit, an electron discharge tube comprising a cathode and anode for producing an electron space current, control means including circuit connections from said input circuit to said tube for varying said space current in accordance with said signal wave, an electrostatic control electrode in said tube, means for producing a concentrated variable electron space charge adjacent to said control electrode, an output circuit for said tube, the input-output frequency characteristic of said system having a band width sufficient to pass said carrier and side frequency band, resonant impedance means connected to said control electrode and cathode, said impedance means having a frequency response characteristic of substantially reduced band width compared with said input-output characteristic and having its center

frequency detuned relative to said carrier frequency to cause a displacement current to be induced therein by said space charge and to establish a potential upon said control electrode for discrete components of said signal wave of such phase as to modify said input-output frequency response characteristic, and means to provide a high impedance direct current return path from said grid to said cathode.

3. In a system for translating a modulated carrier signal wave comprising a carrier and a predetermined band of side frequencies, an input circuit, an electron discharge tube comprising a cathode and anode for producing an electron space current, control means including circuit connections from said input circuit to said tube for varying said space current in accordance with said signal wave, an electrostatic control electrode in said tube, means for producing a concentrated variable electron space charge adjacent to said control electrode, an output circuit for said tube, the input-output frequency characteristic of said system having a band width sufficient to pass said carrier and side frequency band, resonant impedance means connected to said control electrode and cathode, said impedance means having a frequency response characteristic of substantially reduced band width compared with said input-output characteristic and having its center frequency tuned to a predetermined side frequency of said signal wave to cause a displacement current to be induced therein by said space charge and to establish a potential upon said control electrode for discrete components of said signal wave of such phase as to modify said input-output frequency response characteristic.

4. In a system of the character described, an input circuit traversed by a modulated signal current comprising carrier and side band frequencies, an electron discharge tube including means for producing an electron space current, control means including circuit connections from said circuit to said tube for controlling said space current in accordance with said signal current, an output circuit for said tube, said input and output circuit forming a translation system having a relatively broadly tuned frequency response characteristic of predetermined band width sufficient to pass said signal current, an electrostatic control electrode in said tube, means for producing a concentrated variable electron space charge adjacent to said control electrode, and a relatively sharply tuned resonant impedance device connected to said control electrode and cathode, said impedance device having a response band width substantially less than the signal frequency band being translated and being detuned relative to the carrier frequency to cause a displacement current to be induced therein by said space charge and to develop a signal potential upon said control electrode of such phase as to sharpen the frequency cut-off of the input-output frequency response characteristic of said system.

5. In a system of the character described, an input circuit traversed by a modulated signal current comprising carrier and said band frequencies, a piezo-electric crystal element, an electron discharge tube including means for producing an electron space current, control means including circuit connections from said circuit to said tube for controlling said space current in accordance with said signal current, an output circuit for said tube, said input and output circuit forming a translation system having a frequency response characteristic of predetermined

band width substantially exceeding the width of the response curve of said crystal element, an electrostatic control electrode in said tube, means for producing a concentrated variable electron space charge adjacent to said control electrode, said piezo-electric crystal element being resonant to a predetermined side band frequency of said signal current and connected to said control electrode and cathode to cause a displacement current to be induced therein by said space charge and to develop a signal potential upon said control electrode of such phase as to sharpen the frequency cut-off of the frequency response characteristic of said system.

6. In a system of the character described, an input circuit traversed by a modulated signal current comprising carrier and side band frequencies, an electron discharge tube including means for producing an electron space current, control means including circuit connections from said circuit to said tube for controlling said space current in accordance with said signal current, an output circuit for said tube, said input circuit and output circuit forming a translation system of predetermined frequency band width sufficient to pass said signal current, an electrostatic control electrode in said tube, means for producing a concentrated variable electron space charge adjacent said control electrode, a resonant impedance device having a response band width substantially less than said predetermined band width and being connected to said control electrode and cathode to cause a displacement current to be induced therein by said space charge and to develop a signal potential upon said control electrode of such phase as to substantially accentuate discrete frequencies of the signal current in said output circuit, and means for varying the relative departure of the center resonant frequency of said impedance device from the carrier frequency of said signal current.

7. In a system of the character described, an input circuit traversed by a modulated signal current comprising carrier and side band frequencies, a piezo-electric crystal element, an electron discharge tube including means for producing an electron space current, control means including circuit connections from said circuit to said tube for controlling said space current in accordance with said signal current, an output circuit for said tube, said input and output circuit forming a translation system of predetermined frequency band width substantially exceeding the width of the frequency response curve of said crystal element and sufficient to pass said signal current, an electrostatic control electrode in said tube, means for producing a concentrated variable electron space charge adjacent to said control electrode, said crystal element being connected to said control electrode and cathode to cause a displacement current to be induced therein by said space charge and to develop a signal potential upon said control electrode of such phase as to substantially accentuate a discrete frequency of the signal current in said output circuit, and means for varying the relative departure of the carrier frequency of said signal current from the resonant frequency of said crystal element.

8. In a system for translating modulated signal energy comprising carrier and side band frequencies, an input circuit, an electron discharge tube having means for producing an electron space current, control means including circuit

connections from said input circuit to said tube for controlling said space current in accordance with the amplitude of the signals being translated, an output circuit for said tube, said system having a relatively broad input-output frequency, response characteristic, an electrostatic control electrode in said tube, means for producing a concentrated electron space charge adjacent to said control electrode, resonant impedance means connected to said control electrode, said impedance means having a relatively narrow frequency characteristic and being tuned to a predetermined side frequency.

9. In a system for translating modulated signal energy comprising carrier and side band frequencies, an input circuit, an electron discharge tube having an anode and a cathode for producing an electron space current, control means including circuit connections from said input circuit to said tube for controlling said space current in accordance with the amplitude of the signals being translated, an output circuit connected to said anode, said system having a relatively broad input-output frequency response characteristic, an electrostatic control grid in said tube, means for producing a concentrated electron space charge adjacent to said control grid, and a direct current impedance-shunted piezo-electric crystal element having a relatively narrow frequency response characteristic connected to said control electrode and cathode and resonating at one of said side band frequencies to modify said frequency response characteristic.

10. In a system for translating modulated signal energy comprising carrier and side band frequencies, an input and an output circuit, a pair of electron tube amplifiers connected in cascade between said input and output circuit to provide an input-output frequency response characteristic of said system of relatively broad predetermined band width, electrostatic control electrodes in said tubes, means for producing a concentrated electron space charge adjacent to said control electrodes, and resonant impedance means having relatively narrow frequency response characteristics connected to each of said control electrodes, one of said impedance means resonating at a frequency above and the other impedance means resonating at a frequency below said carrier frequency to sharpen the cut-offs of said response characteristic.

11. In a system for translating modulated signal energy comprising carrier and side band frequencies, an input and an output circuit, at least two electron tube amplifiers having anode and cathode electrodes and connected in cascade between said input and output circuit to obtain an input-output frequency response characteristic of said system of predetermined relatively broad band width, electrostatic control grids in said tubes, means for producing a concentrated electron space charge adjacent to said control grids, a pair of direct current impedance-shunted piezo electric crystal elements each being connected to one of said control electrodes and the cathode of the respective tube, one of said crystal elements resonating at a first frequency above and the other of said crystal elements resonating at a second frequency below said carrier frequency and symmetrical to said first frequency, to sharpen the cut-offs of said frequency response characteristic.
